EDWARD P. JONES, DANIEL W. FALL, AND FRANCIS E. JONES, OF BRECKENRIDGE,
COLORADO.

SAFETY IGNITER.

Application filed September 1, 1923. Serial No. 660,635.

To all whom it may concern:

Be it known that EDWARD P. JONES, DANIEL W. FALL, and FRANCIS E. JONES, citizens of the United States, residing at Breckenridge, in the county of Summit and State of Colorado, have invented certain new and useful Improvements in Safety Igniters, of which the following is a specification.

The present invention relates to safety igniters for all sorts of high explosives, such for example, as are used in blasting, mining, and like operations.

In the fuses or igniters now commonly used, considerable danger is occasioned by hanging of fire, sometimes for many hours, which causes delayed explosions, at an annual cost of many lives in mining and other operations. This danger from hanging fire exists in fuses or igniters of all kinds where 10 in lint or like slow burning materials are used to ignite, confine or are in contact with, the more rapid burning powder or like combustible materials. In fuses of this kind a blank space or break in the powder train 15 has been known to stop the burning of the powder, and the lint or container has smouldered for over 12 hours until the powder has been reignited and caused a fatal explosion.

An object of the present invention is to 20 provide an igniter or fuse in which all possibility of hanging fire with its resulting disastrous consequences is eliminated.

A further object of the invention is to 25 provide a safety igniter wherein the only combustible material used is the rapid burning powder or other fusible or combustible material train which may be readily manufactured for different timing of operation, and in which defects may be seen at a glance.

Another object of the invention is to 30 provide a more simple and efficient igniter and fulminate, or other high explosive cap than has heretofore been produced.

Other objects of the invention will appear 35 in the following detailed description of the preferred embodiments of the invention of which—

Figure 1 is a sectional elevation of a short time train igniter.

Figure 2 is a plan view of the igniter 40 shown in Figure 1.

Figure 3 is a sectional elevation of a long time train igniter.

Figure 4 is a sectional plan view taken 45 along line AA of Figure 3.

Figure 5 is a sectional elevation showing the igniter as applied to a fulminate or high explosive cap.

Figure 6 is a plan view of the form shown in Figure 5.

Referring to Figures 1 and 2, 1 represents a tube made of porcelain, cement, glass or other transparent and noncombustible materials. A passage 2 extends through the main portion of 1 and connects at the top 60 with a larger recessed or chamber portion 3. Passage 2 and part of recess 3 is filled with powder or like combustible material 4. A coating 5 of easily fusible and preferably combustible material, for example water 65 glass, wax, or paraffin is spread over the lower end of 1 and serves to seal material 4 in place in the passage and to maintain this material in dry condition. Coating 5 is thin 70 enough to be broken by the burning train. 75 The upper end of recess 3 is then sealed hermetically with a plug 6 of cement paste, or like material. Sealed into and extending through plug 6 are electrical conductors 7 and 8 which are bent and shaped to form a 80 pair of spark points in the part of chamber 3 containing material 4. Wires 7 and 8 are properly insulated from each other and if desired, an insulating cover 9 may be provided to cover both.

In operation, wires 7 and 8 are connected 85 to a source of electrical energy such as a battery or magneto and a spark is jumped between the points of 7 and 8 in well known manner. This ignites the material 4 which 90 then burns through passage 2 and plug 5, and ignites a high explosive or charge with which it has been placed in contact.

The material in passage 4 burns at a definite rate for a given material and the time 95 before the material will have burned through to the high explosive will be determined by the length of the passage. Accordingly, to make a quick acting igniter, passage 2 is shortened and to make a slow acting igniter 100 passage 2 is lengthened. It will therefore be obvious that by cutting off the tube 1 properly, any desired timing may be obtained.

To avoid the necessity of making the body 105 1 inconveniently long for slower timing of operation, passage 2 may be made in a winding or helical form as shown by passage 2' in Figures 3 and 4. The remaining 110 structure of this form is, as indicated by

the reference numerals, the same as shown in Figures 1 and 2.

In Figures 5 and 6, an igniter as set forth in Figure 1 is shown as applied to a form of fulminate cap. In a cap as disclosed the seal 5 may be omitted. A container 10 has the lower end thereof filled with dynamite or fulminate 11. A rubber packing or washer 12 provided with a perforation 13 is placed over and acts as a yielding buffer between fulminate 11, and the body 1 of the igniter. Perforation 13 permits the burning material 1 to ignite fulminate 11. The igniter fits snugly into container 10 and is sealed tightly therein by means of paste or cement plug 14 through which wires 7 and 8 extend. Ignition of the cap occurs in the manner explained for the fuse. The interposition of washer 12 between the 20 igniter and the fulminate adds considerably to the safety of the cap during manufacture and other necessary handling.

It will be seen that all possibility of hanging fire has been removed in the construction disclosed by the complete elimination of all slow burning materials such as lint. If the time train should happen to be defective no harm can result. Furthermore, if the body 1 is made of transparent material such as glass, any blank or empty spaces in the time train or other defects can immediately be seen and the defective igniters may be discarded. This arrangement will permit of convenient inspection immediately before use, and the use of trans-

parent materials to confine the time train is an important feature of the invention.

Having described and shown preferred embodiments of the invention, what is desired to be secured by Letters Patent and 40 claimed as new is:

1. An igniter comprising a body of incombustible material, an igniting chamber formed in the upper end of said body, a pair of electrical spark points sealed into 45 said igniting chamber, a helical passage connecting with said chamber and extending through said body, and combustible material confined in said passage to form a time train. 50

2. A high explosive cap embodying a container and a high explosive in said container; an igniter comprising a body of incombustible material, a passage or opening 55 formed in and extending through said body, combustible material confined in said passage to form a time train, and means for igniting said combustible material; and a member of yielding material interposed between said high explosive and said igniter. 60

3. The combination as set forth in claim 2 in which said member is comprised of rubber and has a perforation connecting the lower end of said time train with said high explosive. 65

Signed at Breckenridge, Colo., this 12 day of Aug., 1923.

EDWARD P. JONES.

D. W. FALL.
